UNITED STATES PATENT OFFICE

117,256

DESIGN FOR A JACKET

William Cohn, Mount Vernon, N. Y.

Application August 15, 1939, Serial No. 86,690

Term of patent 3½ years

To all whom it may concern:

Be it known that I, William Cohn, a citizen of the United States and residing at Mount Vernon, in the county of Westchester and State of New York, have invented a new, original, and ornamental Design for a Jacket, of which the following is a specification, reference being had to the accompanying drawings, forming part thereof, and in which

Fig. 1 is a front view of a jacket showing my new design, and

Fig. 2 is a rear view of the jacket.

I claim:

The ornamental design for a jacket, as shown.

WILLIAM COHN.
